US00D878315S

(12) **United States Design Patent** (10) **Patent No.:** **US D878,315 S**
(45) **Date of Patent:** **** Mar. 17, 2020**

(54) **COMMUNICATION DEVICE**

(71) Applicant: **Hand Held Products, Inc.**, Fort Mill, SC (US)

(72) Inventors: **Peng Zhou**, Jiangsu (CN); **Giles Richard Hemmings**, Bromyard (GB); **Xianwei Yan**, Jiangsu (CN); **Xiaofang Yang**, Jiangsu (CN)

(73) Assignee: **HAND HELD PRODUCTS, INC.**, Fort Mill, SC (US)

(**) Term: **15 Years**

(21) Appl. No.: **29/627,523**

(22) Filed: **Nov. 28, 2017**

(30) **Foreign Application Priority Data**

Jun. 2, 2017 (CN) 2017 3 0219886

(51) **LOC (12) Cl.** **14-03**

(52) **U.S. Cl.**

USPC **D14/137; D10/104.1**

(58) **Field of Classification Search**

USPC .... D14/137, 138 R, 138 AA, 147, 148, 218, D14/155, 159, 142, 225, 226, 191, 172, D14/243, 204, 217, 188, 192, 194, 197, D14/198; D21/517, 566; D10/104.1, D10/104.2, 106.1, 65, 70; D13/168; D30/199

CPC H04B 1/3833; H04B 1/3827; H04B 2001/3861; H04M 1/0202; H04M 1/03; H04M 1/035; G08B 21/0202

See application file for complete search history.

(57) **CLAIM**

The ornamental design for a communication device, as shown and described.

DESCRIPTION

FIG. 1 is a front perspective view of a communication device of the present invention;

FIG. 2 is a front elevation view of the communication device of FIG. 1;

FIG. 3 is a rear elevation view of the communication device of FIG. 1;

FIG. 4 is a left elevation view of the communication device of FIG. 1;

FIG. 5 is a right elevation view of the communication device of FIG. 1;

FIG. 6 is a top plan view of the communication device of FIG. 1; and,

FIG. 7 is a bottom plan view of the communication device of FIG. 1.

The broken lines shown herein are for illustrative purposes and form no part of the claimed design.

1 Claim, 5 Drawing Sheets
